UNITED STATES PATENT OFFICE.

ELMORE D. CODY, OF ERIE, PENNSYLVANIA, ASSIGNOR OF ONE-HALF TO
JOHN W. HOYS, OF SAME PLACE.

STEAM CAR-HEATER.

SPECIFICATION forming part of Letters Patent No. 329,017, dated October 27, 1885.

Application filed August 11, 1884. Serial No. 140,272. (No model.)

To all whom it may concern:

Be it known that I, ELMORE D. CODY, a citizen of the United States, residing at Erie, in the county of Erie and State of Pennsylvania, have invented certain new and useful Improvements in Steam Car-Heaters; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to improvements in mechanism for heating railway passenger-cars by means of steam or hot water, and improvements in piping railway passenger-cars for such purpose.

The objects of my invention are, first, to provide a supply-pipe for furnishing steam or hot water for heating railway passenger-cars communicating with heating-drums placed in inclosed chambers under the floor near each end of the car, and also near the center of such car, with branch pipes supplying hot water or steam to the upper courses of coils along the sides of such car; second, to provide the lower courses of the coils along the side of a car with return-bends and pipes connecting the same with a steam-trap placed under the car, by means whereof a constant circulation of live steam is kept up through the steam-drums hereinbefore referred to, and also through the coils along the side of the car. However, when hot water is used, the said return-bends, instead of communicating with the traps, as aforesaid, communicate with a return-pipe for conducting the partially cooled water back to the heater; third, a system of piping for heating railway passenger-cars by means of steam or hot water, substantially as hereinbefore suggested, by means whereof steam or hot water is delivered to heaters under the floor near the ends of the car, and also to the central portions of coils along the sides of the car, and the condensed steam or partially-cooled water taken therefrom at or near the center of the car, whereby the coils along the side of the car are at all points kept at substantially the same

temperature and the heat substantially equalized throughout all portions of the car.

Other features of my invention appear hereinafter in the specification and claims.

I accomplish these objects and results in the manner and by the mechanism illustrated in the accompanying drawings, in which—

Figure 1 is a perspective view of a portion of a railway passenger-car, showing my improvements therein and the coils and connections thereof on one side of such car. Fig. 2 is an end view in section of a railway passenger-car, showing a cross-section of my device on the lines *x x* and *y y* (in the direction of the arrow *z z*) in Fig. 1. Fig. 3 is a side elevation of my device in a railway passenger-car, portions of the car, the coils, and the pipes being broken away.

Like letters refer to like parts in all the figures.

In the construction of my device I first place under the floor of a passenger-car a supply-pipe, A, extending from end to end of the car, having suitable couplings, A', upon the ends thereof, and having cut-off valves *a a* placed at convenient points in said supply-pipe.

Near each end of the car, in inclosed chambers under the floor thereof, and communicating with the supply-pipe A, I place steam or hot-water cylinders B B, (or steam-pipe coils 80 in lieu thereof,) preferably directly over the supply-pipe A, said chambers communicating with the inside of the car C by means of heat-registers D D and cold-air registers E E, placed in the floor of the car. Near the center of the supply-pipe A, I place a cross, F, from which toward either side of the car extend pipes F' F' to a sufficient distance to reach the ends of the seats on either side of the aisle in the car, from which upright pipes F'' F'', extending 90 upward through the floor of the car under the seat G, (preferably one of the central seats of the car,) next to the aisle, and upon the top of the upright pipes F'' F'', I place angle-valves f f, from which valves pipes F''' F''' extend to 95 the upper courses of the coils H, extending along either side of the car for supplying steam or hot water to said coils. From the lower courses of the coils H, and preferably under the first seat I on the other side of the

center of the car, I place return-bends J J, which extend under the seat nearly to the aisle, where they connect by T's projecting downward through the floor of the car, where 5 these T's connect with pipes L L', &c., (arranged in any convenient shape,) communicating with the steam-trap M, by means whereof the system of steam-pipes hereinbefore referred to are constantly drained, thereby insuring a 10 continuous circulation of live steam through all portions of the heating mechanism of the car. In the operation of this device the steam-drums B B drain directly into the supply-pipe A, where the live steam forces the water of 15 condensation through the system of pipes F' F' F² into the upper courses of the coils H, thence down through the return-bends J J and the pipes L L', &c., into the steam-trap M, from whence it escapes, thereby insuring 20 at all times a free and complete circulation of live steam through all portions of the heating apparatus of the car.

The valves or cocks a a in the supply-pipe A are used simply to cut off the steam when 25 the car in which the apparatus is used is the last one on a train. When in the center of a train, however, the cocks or valves a a in the supply-pipe A are left open, so as to permit the passage of steam from one car to another.

30 To prevent condensation in the supply-pipe A, by reason of its being exposed under the car, it may be boxed or covered with any of the non conducting materials commonly used in covering steam-pipes to prevent condensation.

35 In illustrating the inside of the car C, but two seat-frames are shown, G and I, the same being shown as the two seats nearest the center of such car, under one of which, G, the hot steam 40 is supplied to the side coils, H, and under the other of which, I, the condensed water is removed from the lower section of the coils H. In illustrating the coils H on the side of the car but two pipes are shown. However, in 45 piping a car, any number of pipes may be used that is desired. In making the connections F' F' F², and also the connections L L', &c., to the trap M, they may be varied in shape to suit the convenience of the mechanic, placing 50 the same in the car as his judgment may dictate, the peculiar shape of the connections shown not being essential to my invention.

The steam-drums B B, hot-air registers D D, and cold-air registers E E are placed near the 55 ends of the car to equalize the heat throughout all portions of the car, cold air being drawn in at the registers E E and heated by the steam-drums B B and delivered back into the car through the hot-air registers D D near 60 the ends of the car.

In case hot water is used for heating cars by 65 my system of piping, a return-pipe, N, (shown in dotted lines in Fig. 1,) communicating with the pipe L, (used to convey the steam to the trap M,) may be used to convey the partially cooled water back to the heater, in which case the steam-trap M is not required. This modi-

fication is only necessary, however, when hot water is used to produce the heat instead of live steam.

I am aware that coils along the sides of cars and return-bends under the seats of cars are in common use for heating railway-cars by means of hot water or steam. A device having pipes along the sides of the car is shown in the patent to Slingland, No. 284,250, dated September 4, 1883; but to operate the mechanism described in that patent a steam-boiler under the center of the car is necessary. In the patent to McDuffey and Jaques, No. 185,137, dated January 21, 1873, an inclosed chamber in the floor of the car supplied with hot-water or steam pipes is shown. In neither of these devices is any means provided for adequately heating the ends of the car, except the ends 85 of the coils along the sides of the car, shown in one of the patents referred to; neither does either device show any means for adequately discharging the water of condensation, (except the steam-boiler shown in Patent No. 284,250.) 90

I am also aware that the patents of Graydon, No. 212,375, and of Farwell, No. 82,210, show and describe certain means for discharging the water of condensation from the pipes of car-heaters, in that of Graydon it being 95 drained into tanks at each end of the car, from which it can be discharged from time to time by opening cocks connected with discharge-pipes; but this device is not in any wise automatic in its operation, the tanks simply operating as catch-basins for the drainage from the pipes. In that of Farwell, however, a trap is shown near each end of the car, two traps being necessary in the operation of his device, which, however, is all located in chambers under the floor of the 105 car. These traps operate automatically to discharge a portion of the water reaching the trap, but not all of it, so that in cold weather, when the car was disconnected from the train, it would certainly freeze and become useless. 110 In none of the devices referred to are the same or as good results obtained as I do, in that I first supply hot steam to self-draining drums under the floor at either end of the car; second, I supply hot steam to the upper courses of 115 coils in the car at or near its center longitudinally on both sides of the car, this steam traveling both ways to the ends of the car in pipes inclined downward toward the ends of the car, and on its return it travels from the 120 ends of the car in the lower courses of the pipes, which incline downward to the center of the car, where they connect with a common waste-pipe ending in an automatic discharge-trap under the central portion of the 125 car. By this means the hottest part of the upper courses of the side coils is opposite the coldest part of the lower courses of the side coils, by which means the average heat of the upper and lower courses of the side coils is 130 uniform throughout the entire length of the car, and to provide for extra heat near the ends of the car the side coils are at these points supplemented by the drums under the

floor, communicating with the car by means of registers in the floor; and, again, by my arrangement of the heating mechanism I drain all parts of the heating apparatus into a common trap, which operates automatically to discharge all of the water of condensation, so that a car fitted with my heating device may be cut out of a train at any time in the coldest weather, and the pipes and traps will instantly empty themselves of any and all water therein, so that no part of them will freeze. Therefore I do not claim, broadly, the heating of cars by systems of steam or hot-water pipes; but

What I do claim as new, and desire to secure

15 by Letters Patent of the United States, is—

1. A system of piping for heating railway passenger-cars, consisting of a supply-pipe extending longitudinally under the central portion of a car communicating with steam 20 drums or coils inclosed in chambers under the floor of such car, in combination with pipes extending from the central portion of said supply-pipe to the upper courses of coils of pipe along the sides of such car, and escape- 25 pipes from the central portion of the lower courses of said coils, communicating with and draining into a steam-trap under the floor of the car, substantially as and for the purpose set forth.

30 2. In a railway-car heater, side coils, H H,

on either side of the car, substantially as shown, in combination with the continuous steam-supply pipe A under the body of the car, intermediate connections near the center of the car between the upper courses of the 35 side coils, H H, and the supply-pipe A, an automatic steam-trap, M, under the central portion of the car, and intermediate connections between the lower courses of the side coils, H H, and the steam-trap M, substantially as and for the purpose set forth.

3. The combination, in a railway-car heater, of a steam-supply pipe, A, extending under the body of the car from end to end thereof, and communicating near each end of the car with 45 steam-drums B B in chambers under the floor of the car, and communicating near the center of the car with the upper courses of both of the side coils, H H, with an automatic steam-trap, M, communicating near the center of the 50 car with the lower courses of both of the side coils, H H, substantially as and for the purpose set forth.

In testimony whereof I affix my signature in presence of two witnesses.

ELMORE D. CODY.

Witnesses:

H. M. STURGEON,
F. A. SAWDEY.

It is hereby certified that the name of the assignee in Letters Patent No. 329,017, granted October 27, 1885, upon the application of Elmore D. Cody, of Erie, Pennsylvania, for an improvement in "Steam Car Heaters," was erroneously written and printed "John W. Hoys;" that said name should have been written and printed "John W. Hays; and that the said Letters Patent should be read with this correction therein that the same may conform to the record of the case in the Patent Office.

Signed, countersigned, and sealed this 3d day of November, A. D. 1885.
